SWITCHING SYSTEM

John H. Brundage, Cocoa, Fla., assignor to International Telephone and Telegraph Corporation, a corporation of Maryland

Application February 1, 1952, Serial No. 269,486

8 Claims. (Cl. 340—253)

1

This invention relates to a novel automatic electric switching system which is adapted to maintain a predetermined output signal, and particularly to such a system which may be associated with a carrier telephone system and which is responsive to faulty signal generation therein.

This system is particularly adapted for operation in conjunction with multi-supply sources, for example, a primary source of supply and an auxiliary source of supply both having identical operating characteristics and each coupled to an output circuit. If the electrical energy, supplied from the primary source, deviates from predetermined limits, the switching circuit automatically cuts-out the primary source and cuts in the auxiliary source, to provide suitable and continuous electrical energy to the output thereof.

An object of the invention is to provide an electric switching arrangement having a tripping circuit connected in a novel manner to automatically switch the output from a faulty supply source to an adequate substitute supply source.

Another object of my invention is to provide a novel arrangement including a connection from the output of the system to the tripping device, whereby the device remains in its tripped position, actuating an alarm to indicate a faulty supply source.

A feature of my invention is to provide a switching arrangement which is controllable to originally couple either of two sources of supply to the output circuit.

In accordance with one aspect of the invention there is provided an electrical switching system comprising primary and auxiliary sources of electrical energy, an output circuit and means for alternatively coupling the sources of energy to the output circuit. The primary source is adapted to feed the output circuit during normal operation of the system and the auxiliary source is adapted to feed the output circuit during faulty operation of the primary source. The means for alternatively coupling the sources of energy to the output circuit comprises a pair of conductive devices having their outputs connected to the output circuit. Each of the conductive devices has at least two control elements. The primary source of energy is connected to a first control element of one of said devices and the auxiliary source is connected to a first control element of the other conductive device. A trippable device is provided for controlling the sequence of operation of the conductive devices and also has at least two control elements. A biasing circuit is coupled from

2

a first control element of the trippable device to the first element of the one conductive device and to the second control element of the other device. Means are coupled to the first element of the other device for rendering it normally non-conductive. The trippable device is connected to the output whereby a portion of the output energy is applied thereto. The biasing circuit is adjusted for biasing the one device conductive and the other device non-conductive while the primary source is delivering a normal signal to the output circuit. Upon the primary source delivering a faulty signal, the trippable device is tripped and produces a change in the biasing circuit whereby said one device is rendered non-conductive and the said other device is rendered conductive and as a result thereof, the output circuit is switched from the primary source to the auxiliary source. Means are provided for untripping the trippable device for removing the change in the bias circuit and therefore switch the supply sources to their original connections.

In accordance with a more specific embodiment of the invention, electron tubes are provided for the conductive devices and a gas discharge tube is used for the trippable device.

The above mentioned and other features and objects of this invention and the manner of attaining them will become more apparent and the invention itself will be best understood by reference to the following description of an embodiment of the invention taken in conjunction with the accompanying drawing, wherein there is illustrated a schematic diagram of an electronic switching system.

Referring to the figure, there is provided an electrical switching system comprising primary and auxiliary sources of electrical energy, having identical electrical operating characteristics, coupled via a switching circuit to an output circuit.

The switching circuit comprises a pair of electron tubes 1 and 2, respectively, having their outputs connected in parallel to the output circuit over a load resistor 3. The output circuits are connected in a parallel, in a null-T-type network, whereby the output from either source is identical to the other source when switching is effected.

Each of the electron tubes 1, 2 may be of the triode type having an anode, a control grid and a cathode. The primary and auxiliary sources of electrical energy are connected via condensers 4 and 5 to the control grids of electron tubes 1 and 2 respectively. The grid of tube 1 is connected to a resistor 6 serially connected with a capacitor

7 to ground, and the grid of tube 2 is connected to a resistor 8 serially connected with a capacitor 9 to ground. Tube 1 is self-biased by a cathode biasing circuit comprising a resistor 10 in parallel with a capacitor 11; the parallel combination being connected at one end to ground. The bias for the cathode of tube 2 is provided by a B+ source of supply over a voltage divider network comprising resistors 12 and 13 in series with a parallel circuit having a resistor 14 in shunt with a capacitor 15; the parallel circuit being connected to ground at one end.

A manually operable switch 16 controlling contacts 16a, 16b, 16c and 16d is provided to connect the grid circuits of tubes 1 and 2 to ground and biasing circuit 10, 11, respectively, and to connect the cathodes of tubes 1 and 2 to biasing circuits 10, 11 and 14, 15, respectively, depending on whether the switch is positioned to connect the primary source to the output or the auxiliary source to the output. As shown in the drawing, the switch is positioned to connect the primary source to the output.

A tripping device in the form of a gas discharge tube 17, having a cathode, a control grid and an anode, is provided for sequentially or alternatively coupling the primary and auxiliary sources to the output. A portion of the output energy is coupled via line 18, rectifier 19, to a grid biasing circuit 20 consisting of a resistor 22 connected in parallel with a capacitor 23, and a resistor 24 coupled as a potentiometer to the control grid of the gas discharge tube. A resistor 21 is connected to the grid of tube 17. Since the output voltage is A.-C., a rectifier 19 is provided to rectify the energy applied to the grid biasing circuit of tube 17. Capacitor 23 is thereby charged to a given voltage which voltage will drop if the output current fails. Resistor 22 and capacitor 23 provide a suitable time delay in the biasing circuit. The time delay may be such as to permit a failure of current in the output circuit to exist for a limited time before effecting operation of the gas tube.

The cathode biasing circuit 10, 11 for tube 1 is connected to the cathode of the gas discharge tube 17 via resistor 25. This cathode biasing circuit is connected in parallel with a resistor 26 and bypass condenser 27 network.

The anode of tube 17 is connected via resistor 28 to a relay 29 controlling switch 30 which actuates an alarm system. The anode potential for tube 17 is provided at 31 via reset switch 32.

Anode resistors 33 and 34 are provided in the plate circuit of tubes 1 and 2, respectively, to apply suitable potential to the anodes thereof.

Indicator circuits 35 and 36, each comprising a pair of resistors and a lamp, may be provided when it is desired to indicate the operation of the particular tube associated therewith. The indicator circuits 35 and 36 are connected across the outputs of tubes 1 and 2, respectively.

The operation of the system is hereinafter explained first, with the switch 16 in the position coupling the primary source with the output, and secondly, in the position shown by the dotted lines in the drawing, coupling the auxiliary source with the output.

The operation of the system with the switch positioned as shown is as follows:

Tube 1 is self-biased by resistor 10 and a capacitor 11 and normally conducts current. The grid return circuit is completed by contact 16a short-circuiting the capacitor 1.

The signal from the primary source is thus allowed to enter, is amplified in the usual manner and is applied through capacitor 37 to the output circuit. A portion of the output of tube 1 is routed to the grid circuit of the gas discharge tube 17, is rectified by the rectifier 19 and is applied across resistors 22 and 24 as grid bias for tube 17. The amount of bias may be varied by the adjustment of resistor 24. As long as the signal from the primary source is of the proper level, the balance of voltages on the grid and on the cathode of tube 17 is such that the tube does not fire, and no current flows through it to relay 29 connected in its plate circuit, or in the cathode circuit thereof.

During the normal operation, tube 2 is non-conductive. By the voltage divider action of resistors 12, 13 and 14, a fixed cut-off bias is provided from the B+ supplied across resistor 14. This bias voltage is positive at the cathode of tube 2. At the same time, the voltage drop across resistor 10 in the cathode circuit of tube 1 is applied through resistor 8 to the grid of tube 2 as positive grid bias for that tube. The balance of voltages at the grid and at the cathode of tube 2 keeps this tube at cut-off during normal operation of the primary source. Since this tube is at cut-off, the signal from the auxiliary source is effectively blocked and cannot enter the output circuit.

When the primary source fails or delivers a faulty signal, the voltage applied to the grid of tube 1 is greatly reduced. The portion of the signal voltage applied to the grid of tube 17 through rectifier 19 is reduced accordingly and the balance of voltages applied to tube 17 is such that the tube fires. The resultant current flows through resistors 10, 25 and 26 and through the coil of relay 29. The increased voltage drop across resistor 10 is positive at the cathode of tube 1, and is sufficiently large to cut off this tube. The same voltage is applied through resistor 8 as a positive voltage to the grid of tube 2. The voltage is high enough to overcome the cut-off bias across resistor 14 in the cathode of tube 2 and to cause this tube to conduct current. As a result of this action, the signal from the primary source is blocked from passing through tube 1 while the signal from the auxiliary source is allowed to go through tube 2 to the output circuit.

Relay 29 becomes energized by the current from tube 17 flowing through it and moves contact 30 to actuate an alarm system which may consist of a lamp and buzzer system (not shown). When the trouble has been cleared, operation of reset button 32 interrupts the current in the gas tube 17. When this happens, the bias voltage distribution returns to the original condition, and provided the primary source is now providing a signal of the proper level, a signal voltage is applied to tube 1. Tube 1 will continue to conduct current, while tube 2 is cut off and blocks the signal from the auxiliary source. The circuit is thus restored to normal. It is to be noted that once tube 17 fires, it will continue firing and the portion of the energy fed back to its grid biasing circuit will have no effect on its operation. Therefore, the auxiliary source will remain coupled to the output until the faulty condition of the primary is noted and reset switch 32 opened.

With the switch 16 moved into the position shown by the dotted lines so that the auxiliary

source is coupled to the output circuit, the operation is as follows:

Tube 2 is self-biased by resistor 10 to conduct plate current. Signals from the auxiliary source are permitted to go through tube 2, are amplified in the usual manner and applied through capacitor 38 to the output circuit. A portion of the signal output of tube 2 is routed through rectifier 19 where it is rectified and applied to tube 17 as cut-off bias, providing the signal level at the input to tube 2 is of the proper value.

At the same time tube 1 is kept at cut-off by the voltage drop across the resistor network 10, 25 and 26. The bias voltage across resistor 10 which is now in the cathode circuit of tube 2 is also applied to the grid of tube 1 as a positive voltage. The difference between the cathode and grid voltages of tube 1, keeps this tube at cut-off and effectively blocks the primary source signal from passing therethrough.

When the signal voltage from the auxiliary falls below the required value, the cut-off bias on the tube 17 is reduced sufficiently to cause the tube to fire. The plate current of tube 17 causes the relay 29 to become energized with the same results described in the first mentioned case. Simultaneously, the cathode current of tube 17 flowing through cathode resistor 10 of tube 2 drives this tube to cut-off and applies a sufficiently high positive voltage to the grid of tube 1 to cause this tube to conduct. As a result, the signal from the auxiliary source is blocked, while the signal from the primary source is permitted to go through tube 1 to the output circuit. Thus the electronic switch changes the status from auxiliary source operation to primary source operation.

While I have described above the principles of my invention in connection with specific apparatus and circuitry, it is to be clearly understood that this description is made only by way of example and not as a limitation as set forth in the objects thereof and in the accompanying claims.

What is claimed is:

1. An electrical switching system comprising primary and auxiliary sources of electrical energy, an output circuit, and means for alternatively coupling said sources of energy to said output circuit whereby the primary source feeds the output circuit during normal operation of the system and the auxiliary source feeds the output circuit upon faulty operation of the primary source, said means comprising a pair of conductive devices having their outputs connected to the output circuit, each of said devices having at least two elements, the primary source of energy being connected to a first element of one of said devices and the auxiliary source being connected to a first element of the other conductive device, a trippable device controlling the sequence of operation of said conductive devices said trippable device having at least two elements, a biasing circuit coupled from a first element of said trippable device to said first element of said one device and to the second element of said other device, means coupled to the first element of said other device rendering it normally non-conductive, a connection from said output to the second element of the trippable device whereby a portion of the output energy is applied thereto, the biasing circuit being adjusted for biasing said one device conductive and said other device non-conductive while the primary source is delivering a normal signal to said output cir-

cuit, and upon said primary source delivering a faulty signal, said trippable device being tripped and producing a change in the biasing circuit whereby said one device is rendered non-conductive and said other device is rendered conductive and as a result thereof, the output circuit is switched from the primary source to the auxiliary source, and means for untripping said trippable device whereby the change in the bias circuit is removed and the supply sources are switched to their original connections.

2. The system according to claim 1, wherein said trippable device is a gas discharge tube.

3. The system according to claim 1, wherein 15 said pair of conductive devices are a pair of electron discharge tubes.

4. An electrical switching system comprising primary and auxiliary sources of electrical energy, an output circuit, and means for alternatively coupling said sources of energy to said output, whereby the primary source feeds the output circuit during normal operation of the system and the auxiliary source feeds the output circuit upon faulty operation of the primary source, said means comprising a pair of electron discharge tubes having outputs connected in parallel with the output circuit, each of said electron tubes having an anode, a control grid and a cathode, the primary source of energy being connected to the grid of one of said electron tubes and the auxiliary source being connected to the grid of the other electron tube, a gas discharge tube having an anode, a control grid and a cathode, a biasing circuit coupled from the cathode of the gas tube to the cathode of said one electron tube and to the grid of said other electron tube, a grid biasing circuit for said gas tube, means including a potential source coupled to the cathode of said other electron tube rendering it normally non-conductive, a connection from said output to said grid biasing circuit whereby a portion of the output energy is applied to the grid of said gas tube, the biasing circuits being adjusted for biasing said one electron tube conductive and said other electron tube non-conductive while the primary source is delivering a normal signal to said output circuit, and upon said primary source delivering a faulty signal to the output circuit, said grid biasing circuit

40 50 55 60 65 70 being responsive hereto, to fire said gas tube thereby producing a change in the biasing circuit coupled to the cathode of said one electron tube and the grid of said other electron tube, whereby said one electron tube is rendered non-conductive and said other electron tube is rendered conductive and as a result thereof, the output circuit is switched from the primary source to the auxiliary source, said auxiliary source supplying the electrical energy to said output circuit while said gas tube is conducting, and means for extinguishing said gas tube, whereby the change in the cathode bias circuit is removed and the supply sources are switched to their original connections.

5. The system according to claim 4 and further comprising an indicator circuit connected across each of said electron tubes, said indicator circuit comprising a lamp, whereby the operation of a particular electron tube is indicated by the lamp associated therewith.

6. The system according to claim 4, wherein said biasing circuit coupled from the cathode of the gas tube to the cathode of said one electron tube comprises a resistor in parallel with a 75 capacitor.

7. The system according to claim 4, wherein said grid biasing circuit comprises a resistor in parallel with a capacitor and a second resistor connected as a potentiometer to the grid of said gas tube, whereby the bias of said gas tube may be varied.

8. The system according to claim 4, wherein said outputs of the electron discharge tubes are connected in a parallel null-T-type network so that the outputs from either of said sources are identical to each other. 10

JOHN H. BRUNDAGE.
